UNITED STATES PATENT OFFICE.

AUGUST A. HENDRICKSON, OF OMAHA, NEBRASKA.

FLOORING-CLAMP.

No. 909,408.

Specification of Letters Patent.

Patented Jan. 12, 1909.

Application filed January 17, 1908. Serial No. 411,367.

To all whom it may concern:

Be it known that I, AUGUST A. HENDRICKSON, citizen of the United States, residing at Omaha, in the county of Douglas and 5 State of Nebraska, have invented certain new and useful Improvements in Flooring-Clamps, of which the following is a specification.

The present invention relates to an improved device for forcing flooring boards closely together when laying the same, and has for its object to provide a simple and inexpensive flooring clamp which will operate in an effective manner to produce the desired 15 result.

The invention further contemplates a device of this character which can be quickly placed in an operative position and manipulated by a single workman.

For a full description of the invention and the merits thereof and also to acquire a knowledge of the details of construction and the means for effecting the result, reference is to be had to the following description 20 and accompanying drawings, in which:

Figure 1 is a perspective view of a flooring clamp embodying the invention. Fig. 2 is a longitudinal sectional view through the same showing the operating lever moved to throw 25 both the pawl and detent into an inoperative position. Fig. 3 is a similar view showing the detent and pawl in operative position.

Corresponding and like parts are referred to in the following description and indicated 30 in all the views of the drawings by the same reference characters.

In the embodiment of the invention shown on the drawing the numeral 1 designates the shoe which is provided with a longitudinal 35 guide way having a pusher bar 3 slidably mounted thereon, the sides of the guide way being grooved and the longitudinal edges of the pusher bar being beveled from opposite sides thereof to form the triangular 40 tongues 4 received within the grooves. The upper and lower faces of the pusher bar are shown as flush with the corresponding faces 45 of the shoe, a rack 5 being formed at the top of the pusher bar and the teeth of the rack 50 being inclined rearwardly and terminating in square shoulders in the usual manner.

Projecting upwardly from the shoe 1 upon opposite sides of the guide way 2 are the standards 6 between which the operating 55 lever 7 is pivotally mounted, one end of the lever being bifurcated and the shank 8 of

a pawl 9 being pivoted between the arms of the bifurcation. This pawl 9 is designed to slip over the teeth of the rack 5 when the operating lever is moved in one direction 60 and to engage the square shoulders of the teeth to force the pusher bar forward when the lever is moved in the opposite direction. A spring 10 is utilized for holding the pawl in correct position, the said spring loosely 65 engaging the pawl and serving to force the pawl downwardly into engagement with the rack when the lever is moved forwardly and to lift the pawl out of engagement with the rack when the lever is moved rearwardly 70 beyond the limit of its effective stroke. This spring 10 is shown in the present instance as projecting from the lever 7 and passing through an eye 11 upon the pawl, the said spring being curved or deflected outwardly 75 away from the lever and terminating in a hook 12 which prevents the spring from being drawn entirely through the eye. For the purpose of preventing rearward movement of the pusher bar while the lever 7 is 80 being swung forwardly and the pawl 9 is slipping over the teeth of the rack a detent 85 13 is utilized, the said detent being pivotally mounted at an intermediate point between the standards 6 and having one end thereof 90 hooked to engage the rack 5 while the opposite end is curved as indicated at 14 and is designed to be engaged by the lever 7 when the same is swung rearwardly so as to lift the pawl 9 out of engagement with the rack. 95 With this construction it will be readily apparent that the pressure of the lever against the curved end 14 of the detent will lift the same away from the rack and that with the pawl and detent thus both moved into an inoperative position the pusher bar can be moved freely within the guide way of the shoe and set at the required position. When the lever is again pushed forward the detent 13 is forced downwardly into an operative 100 position by means of a spring 15 and the pawl 9 caused to engage the rack.

Projecting downwardly from the shoe 1 are the studs 16 which are designed to engage the joists or other members upon 105 which the flooring is being laid in order to hold the shoe firmly in position.

In the operation of the clamp the shoe 1 is held firmly in position by means of the studs 16 and the pusher bar 3 caused to engage the flooring. The lever 7 is then worked back and forth and the pusher bar

thereby caused to force the flooring strips closely against each other, after which they are nailed or secured in position by any suitable means.

5 Having thus described the invention, what is claimed as new is:

1. In a device of the character described, the combination of a shoe, a pusher bar slidably mounted upon the shoe, an operating lever, 10 a pawl loosely connected to the operating lever and coöperating therewith to move the pusher bar forward, a detent for preventing rearward movement of the pusher bar, the said detent being adapted to be thrown out 15 of engagement with the pusher bar when the lever is moved into a predetermined position, and a spring projecting from the lever and having a loose and positive connection with the pawl for holding the same in engagement with the pusher bar during 20 the operation of the device and lifting the pawl out of engagement with the pusher bar when the lever is moved into the said predetermined position.

2. In a device of the character described, 25 the combination of a shoe, a pusher bar slidably mounted upon the shoe, an operating lever, a pawl loosely connected to the operating lever and adapted to engage the pusher bar to move the same in one direction, a detent for preventing movement of the pusher bar in the opposite direction, the lever operating automatically to throw the detent away from the pusher bar when moved into a predetermined position, an eye 30 projecting from the pawl, and a spring carried by the lever and passing loosely through the eye whereby the pawl is normally held in engagement with the pusher bar but is moved away from the same when 35 the lever is thrown into the said predetermined position.

In testimony whereof I affix my signature in presence of two witnesses.

AUGUST A. HENDRICKSON. [L. S.]
